US00D796358S

(12) **United States Design Patent** (10) Patent No.: **US D796,358 S**
Abbott et al. (45) Date of Patent: ** Sep. 5, 2017

(54) **BIODETECTION SYSTEM**

(71) Applicant: **bioMérieux**, Marcy l'Etoile (FR)

(72) Inventors: **Richard Abbott**, Draper, UT (US);
Patrick Riley, Salt Lake City, UT (US);
Michael B. Derrick, Salt Lake City,
UT (US); **Steven Moore**, Salt Lake
City, UT (US); **Ronald William
Mudrow**, Magna, UT (US); **Robin
Peng**, South Jordan, UT (US)

(73) Assignee: **bioMérieux**, Marcy-l'Étoile (FR)

(**) Term: **15 Years**

(21) Appl. No.: **29/543,911**

(22) Filed: **Oct. 29, 2015**

(30) **Foreign Application Priority Data**

Jul. 6, 2015 (EM) 002731935

(57) **CLAIM**

The ornamental design for a biodetection system, as shown and described.

DESCRIPTION

FIG. 1 is a perspective view of a first embodiment of our new biodetection system;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof;

FIG. 8 is a perspective view of a second embodiment of our new biodetection system;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the figures depict unclaimed environment and form no part of the claimed design.
